UNITED STATES PATENT OFFICE

ADOLPH M. ZUCKERMAN, OF NEW YORK, N. Y., ASSIGNOR TO R. HOE & CO., INC., OF NEW YORK, N. Y., A CORPORATION OF NEW YORK

ASSOCIATING MECHANISM FOR WEB PRINTING MACHINES

Application filed January 17, 1931. Serial No. 509,286.

The present invention relates to associating mechanism for web printing machines in which a relatively wide web is cut into ribbons which are associated or brought together face to face, with their edges in alignment and are subsequently cut and folded to form a multi-leaved product.

This result has been produced in the past by leading the full width web through a multiple slitting mechanism after which each of the ribbons thus formed is led over a series of turner bars and rollers to associate it with the other ribbons before they are cut and folded.

This arrangement is objectionable because it is difficult to lead the narrow ribbons around a series of turner bars and keep them running in proper alignment and avoid breaking the web.

In the mechanism herein disclosed, each narrow ribbon passes around but one turner bar and in consequence the several ribbons are held in proper alignment without difficulty and without subjecting them to an excessive strain.

The improved associating mechanism is particularly adapted to printing machines with so-called straight-away folders, where sometimes the web is run straight through the folder, while at other times the web is slit into ribbons which are then collated and run through the folder.

The improved associating mechanism is especially adapted for use with printing machines having folders arranged in line with the printing units and which may be used at one time to print a product having large pages such as a newspaper and at another time to print a product having relatively small pages such as a magazine.

An object of the invention is to provide an improved associating mechanism for a web printing machine, that is adapted to cut a wide web into several ribbons and to associate the ribbons which are then led to a cutting and folding mechanism whereby a multi-leaved product is produced.

Another object of the invention is to provide an improved associating mechanism for a web printing machine that is sometimes

used to print products having large pages and at other times, products having relatively small pages.

It is also an object of the invention to provide an associating mechanism of generally improved construction, that will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in the precise embodiment of the invention herein disclosed may be made within the scope of what is claimed without departing from the spirit of the invention.

The preferred embodiment of the invention is illustrated in the accompanying drawings, wherein:

Figure 1 is a diagrammatic side view of a printing machine and folder such as are used for producing magazines, and showing the arrangement of the improved associating mechanism;

Figure 2 is a similar plan view partly broken away showing the arrangement illustrated in Figure 1;

Figure 3 is a diagrammatic side view of a printing machine and folder such as are used for producing newspapers, and showing web runs that are in common use;

Figure 4 is a plan view of the arrangement shown in Figure 3;

Figure 5 is a view similar to Figure 3 but showing web runs in which the associating mechanism that is the subject of the present invention are employed, in order that a product having relatively small pages may be produced; and

Figure 6 is a plan view of the arrangement shown in Figure 5.

Referring to the drawings, 11 and 11' indicate impression cylinders of a printing machine, while 12 and 12' indicate form cylinders, and inking mechanism is indicated generally at 13 and 13'.

A folder is indicated generally at 14 as

100

shown in Figure 1, and comprises cutting cylinders 15 and 15', a collecting cylinder 16, a folding cylinder 17, a delivery fan 18 and delivery tapes 19.

5 A web roll is indicated at 21 from which a web 22 is led around suitable guide rollers 23 and feeding rollers 24, thence to and between the printing cylinders 11 and 12, thence around guide rollers 25, to and between the 10 printing cylinders 11' and 12', thence around guide roller 26 and compensating roller 27, to guide roller 28, thence around a turner bar 29 to the slitting mechanism, which comprises a slitting roller 31 and slitters 32. It 15 is thus cut into several ribbons, each of which pass around one of the small turner bars 33 and one of the guide rollers 34 from which it passes into face to face relation with the other ribbons and they are associated at the 20 nipping rollers 35. From that point, they pass to the cutting and folding cylinders and the product is delivered in the usual manner.

The machine shown in Figure 1 is of the kind used for producing magazines and hence is provided with an offset web roll shown at 25 36, the web 37 from which is led around guide rollers 38 and between the web 22 and the impression cylinder 11', thus preventing smutting of the side of the web that has been printed by the form cylinder 12. The offset web is then led around guide rollers 39 and re-wound on the roll 41 which rests on the 40 rollers 42.

It will be seen that by this method of associating the several ribbons into which the web is cut that but one turner bar is interposed in the path of the web between the slitting mechanism and the folder, and thus the difficulty experienced when narrow webs are 45 drawn around double turner bars is avoided.

An alternative web run is indicated by dotted lines in Figure 1 and extends from the roller 28 around guide roller 43, compensating roller 44, to guide roller 45 and thence to the nipping rollers 35. This run, it will be noted, by-passes the turner bars and may be used when a full width web is fed to the cutting and folding cylinders, so that the sheets may be delivered separately instead of being associated by passing them 50 around the turner bars.

In Figures 3 to 6 inclusive, the invention is shown as applied to a printing machine that is adapted to print either newspapers or 55 magazines. A typical newspaper printing machine having three perfecting units and a folder is shown, the units being indicated generally by the letters A, B and C and the folder by the letter F. The printing unit A includes impression cylinders A-11 and A-11', form cylinders A-12 and A-12' and inking mechanism indicated generally at A-13 and A-13'.

The folder includes a former indicated at 60 51 and also cutting, folding and delivery

mechanism, not shown. The several printing units and the folder are arranged in line in accordance with the usual practise. The former is one-half the width of the web and is so placed that a one-half width web may be run directly to the former without being turned. Web slitting mechanisms are shown and include the slitting rollers 52 and slitters 53. When printing newspapers, the web 54, that is printed by the printing unit A is led from the web roll 55, around guide rollers 56, to and between the printing cylinders A-11 and A-12, around guide rollers 57, to and between the printing cylinders A-11' and A-12', around guide rollers 58 and around the slitting roller 52 where it is divided into two ribbons that are designated 54a and 54b.

Ribbon 54a passes around guide rollers 59 to the drag roller 61 and thence to the former 51, while ribbon 54b passes around turner bars 62 and 63 which bring it into face to face relation and in alignment with ribbon 54a, and it then passes around guide rollers 64 and to the drag roller 61 where it is associated with the ribbon 54a.

The webs printed by the units B and C follow similar paths from the web rolls 65 and 66 respectively to the folder.

Figures 5 and 6 show the same printing machine that is depicted in Figure 3 but with web runs adapted to produce a magazine or a product having relatively small pages. In this arrangement, the B unit is silenced and webs are being printed by units A and C only, although it will be understood that provision may be made for using the B unit as well. In this arrangement, the web 54, after having been printed by the unit A is led around the roller 52 but the slitters 53 have been removed. The full width web is thus led to and around the turner bar 62 and thence to the slitting roller 67 where it is engaged by slitters 68 and thus cut into ribbons indicated 64c, 64d, 64e, and 64f. The several ribbons are each then led around one of the turner bars indicated by the numeral 69 and the guide rollers 71 which position the several ribbons in face to face relation with each other and they are then led to the drag roller 61 where they are associated and passed over the former 51 to the cutting and folding mechanism.

The web printed by the C unit is likewise turned and then slit into ribbons and led to the folder as shown in Figure 6.

It will be noted that the several ribbons as shown in Figure 6, are presented to the former 51 in the same relation as the ribbons shown in Figure 4 so that a longitudinal fold will be made in the center of the ribbons as they pass over the former. The arrangement thus permits the production of a newspaper or a product having relatively large pages by leading the webs as shown in Figure 120 125 130

4 or a product having relatively small pages by leading the webs as shown in Figure 6.

What I claim is:

1. In a mechanism for slitting a web into several ribbons, associating the ribbons and then severing them to form a cut product; a multiple slitting mechanism, a web cutting mechanism, and associating means between the slitting mechanism and the cutting mechanism; said associating means including 10 guide rollers, and only one turner bar in the path of each ribbon.

2. In a web printing and folding machine, a printing unit, a folder in line with the unit, means for leading a full width web to and from the printing unit, a turner bar adapted to turn the full width web, a slitting mechanism adapted to slit the web into several ribbons, short turner bars to which the ribbons are led from the slitting mechanism, and 20 guide rollers to which the ribbons are led from the short turner bars and from which they are led to the folder.

3. In a web printing and folding machine for producing either newspapers or magazines, a perfecting printing unit, a folder having a former in longitudinal alignment with the printing unit, means for slitting the web into two ribbons and associating the ribbons to form a product having large pages, and for slitting the web into several ribbons and associating the several ribbons to form a product having relatively small pages; said means including a multiple slitting mechanism, guide rollers, and not more than one 30 turner bar for each ribbon around which the ribbon passes in its movement from the slitting mechanism to the folder.

4. In a web printing and folding machine, a printing unit, a folder in line with the unit, means for leading a web to and from the unit, a turner bar arranged to deflect the web and direct it to one side of the machine, a multiple slitting mechanism adapted to slit the deflected web into several ribbons, a set 45 of turner bars to red deflect the ribbons toward the folder, and guide rollers to which the ribbons are led from the said turner bars and from which they are led to the folder.

5. In a web printing and folding machine, a printing unit, a folder having a drag roller, a first means for slitting the web into first and second ribbons and associating the ribbons to form a product having large pages, 55 and a second means for slitting the web into several ribbons and associating the several ribbons to form a product having relatively small pages; said first means including a slitting mechanism, double turner bars adapted 60 to turn the first ribbon and direct it in face to face relation with the second ribbon, and guide rollers around which the ribbons are led to the drag roller; said second means including a full width turner bar which may 65 be one of the said double turner bars, a mul-

tiple slitting mechanism, a single separate turner bar for each of the several ribbons to which they are led from the slitting mechanism and from which they are led in face to face relation with each other, and guide 70 rollers around which the ribbons are led to the drag roller.

In testimony whereof I affix my signature.

ADOLPH M. ZUCKERMAN.
